UNITED STATES PATENT OFFICE

111,854

DESIGN FOR A SUSPENDER LOOP

Oscar E. Kratz, Kansas City, Mo., assignor to H. D. Lee Mercantile Company, Kansas City, Mo., a corporation

Application August 8, 1938, Serial No. 79,192

Term of patent 14 years

To all whom it may concern:

Be it known that I, Oscar E. Kratz, a citizen of the United States, residing at Kansas City, in the county of Jackson and State of Missouri, have invented a new, original, and ornamental Design for Suspender Loops, of which the following is a specification, reference being had to the accompanying drawing, forming a part thereof, in which:—

Fig. 1 is a top face view of a suspender loop showing my new design;

Fig. 2 is an edge view thereof;
Fig. 3 is a bottom plan view thereof; and
Fig. 4 is a transverse section thereof taken on the line 4—4 of Fig. 1.

The characteristic feature of the suspender loop resides in the specific configurations, proportions, and ornamentation applied thereto, as shown.

I claim:—

The ornamental design for a suspender loop, as shown and described.

OSCAR E. KRATZ.
